UNITED STATES PATENT OFFICE.

FREDERICK C. SCHOFIELD, OF LYNCHBURG, VIRGINIA, ASSIGNOR TO UNITED CIGARETTE MACHINE CO., INC., OF LYNCHBURG, VIRGINIA, A CORPORATION OF VIRGINIA.

TOBACCO-STEMMING MACHINE.

Application filed January 27, 1922. Serial No. 532,182.

To all whom it may concern:

Be it known that I, FREDERICK C. SCHOFIELD, a citizen of the United States, and resident of Lynchburg, in the county of 5 Campbell and State of Virginia, have invented certain new and useful Improvements in Tobacco-Stemming Machines, of which the following is a specification.

This invention relates to a tobacco stemming machine and more particularly to a tobacco stemming machine of the type in which the tobacco leaves are drawn through rotatable stemming devices; and has special reference to the provision of a stemming 10 machine of this kind in which the stemming devices are operative and effective for efficiently removing the web or laminæ of the leaves from the stem by a draw-cutting or draw-cleaving action.

15 In prior forms of machines of the type referred to, the tobacco leaves are gripped either at their butt or tip ends and are drawn through rotatable stemming devices which operate to remove the laminæ or web of the leaves by a scraping, sluffing or cutting action. In the form of machine where stemming is obtained by cutting the web of the leaves from the stems, a number of disadvantages are inherently present which it 20 is the object of this invention to overcome. One of the disadvantages or defects, for example, in this form of machine resides in that the cutting mechanism has a tendency to cut into the stems themselves, weakening 25 the stems and causing them to tear, it being difficult particularly to effect a cutting of the lamina close up to the stems without unduly cutting the stems. It has been further found that in removing the lamina by 30 drawing the leaves through the cutting stemming mechanism, considerable strain has to be exerted on the stems, with the result that many of the stems, although in 35 good condition, are broken during stemming activity. It is well known, moreover, that the tobacco leaves when ready for stemming carry quantities of sand and other gritty earthy substances which, during stemming activity, grind away the cutting mechanism, dulling or distorting the same, this 40 resulting in a lessened efficiency of the machine and in the necessity of replacing or renewing the cutting mechanism after a short operating period. A prime desidera-

tum of my present invention comprehends 55 the provision of a tobacco leaf stemming machine in which these disadvantages inherent in prior machines will be largely overcome and in which the cutting of the leaf web may be effected cleanly close up to 60 the stem and without subjecting the stem of the leaf to too large or great a strain, stemming being effected without cutting or breaking the stems and without cutting the web unduly, the cutting mechanism being, 65 furthermore, so constructed as not to be dulled or distorted by the grinding action of the gritty material carried by the leaves.

The principal objects of my invention may be said to include, besides the provision 70 of a stemming machine having the characteristics and effecting the results above referred to, the further provision of a stemming machine in which the stemming mechanism includes thin flexible blades radially stiff and laterally flexible, the blades having preferably a uniform thinness so 75 that the grinding action does not dull the same, the flexibility of the blades accommodating the stems and varying thicknesses 80 of the same; the further provision of a machine of this kind in which the leaves are drawn through rotatable stemming devices each provided with thin flexible blades of 85 the nature referred to, the blades of the devices intermeshing and being contoured to permit the leaves to be fed and threaded through succeeding blades of the said stemming devices; the further provision of a machine of this kind in which the stem may 90 be cut or severed intermediate its ends and close to its tip; the still further provision of a stemming machine in which the leaves are advanced and drawn through the blades in 95 a direction such that the stem is caused to thread and be fed through the successive intermeshing blades; the still further provision of a stemming machine in which a novel gripping means is provided for securely taking hold of the butt ends of the stems and drawing the same through the stemming mechanism and the provision of a machine of the nature referred to in 100 which the parts are correlated for efficient cooperation and for easy control by an operator.

To the accomplishment of the foregoing and such other objects as may hereinafter

appear, my invention consists in the elements and their relation one to the other, as hereinafter particularly described and sought to be defined in the claims, reference 5 being had to the accompanying drawings which show a preferred embodiment of my invention and in which:

- Figure 1 is a plan view of my stemming machine,
 10 Figure 2 is an enlarged plan view of a portion thereof,
 Figure 3 is an elevational view with parts broken away and parts shown in section,
 15 Figure 4 is an enlarged view of the stemming elements or devices,
 Figure 5 is a cross sectional view of the stemming devices and showing the relation between the stemming mechanism and the gripper mechanism,
 20 Figure 6 is a view showing the cutting means associated with the gripper mechanism,
 Figure 7 is a cross sectional view of a butting device,
 25 Figure 8 is a view of a moistening means associated with the gripper mechanism, and
 Figure 9 is a view showing the manner of operation of the stemming blades.
 Referring to the drawings, the stemming
 30 or stripping machine comprises essentially the feeding means F for advancing the tobacco leaves fed thereto by an operator, the butting mechanism B or B' for removing the lamina of the leaves from the butt ends thereof, the gripper mechanism G which
 35 functions to receive the leaves from the feeding mechanism and for drawing the same in gripped condition to and through the stemming means S.
 The feeding mechanism F comprises preferably a lower conveyer belt 10 trained over the opposed drums 11 and 12 journaled in upstanding brackets 13 and 14 respectively, the bracket 14 being fixedly attached to the
 45 supporting framework 15 and the bracket 13 being slidably mounted thereon and adapted to be adjusted and locked in position by the adjusting means 13'. The conveyer or carrier belt 10 is adapted for receiving the tobacco leaves spaced thereon by an operator at the left of the machine, as viewed in Figure 1, the said conveyer belt being positively driven to advance the leaves to the right (as viewed in Figure 1) for
 50 stemming activity, the operator placing the tobacco leaves upon the carrier belt with the butt ends of the stems against the gauge board 9 to line the stems as much as possible. Cooperating with the conveyer belt 10 I provide the overlying belt or chain 16 trained and movable over oppositely positioned pulleys 17 and 18, the latter being fixed to the shafts 19 and 20 respectively, journaled in sockets 21 and 22 of a transverse bar 24, the shaft 19 being supportingly

journalled in a boss 10' fixedly attached to the framework of the machine. The overlying belt or chain 16 is adapted to ride over the conveyer belt 10 and receive motion therefrom, the chain 16 comprising a binder 70 or clamping belt and cooperating with the conveyer belt 10 for advancing the tobacco leaves therebetween. The bar 24 and the chain and sprockets carried thereby is, by this construction, adapted to swing about 75 the boss 19', the other end of the bar being therefore free to rise, the gravity of the parts being depended upon to give sufficient pressure to carry the leaves forward.

During the feeding of the leaves by the 80 conveyer and clamping belts the butt ends of the leaves may be subjected to a butter for effecting the removal of the web or lamina from the butt ends of the leaves. To this end I may provide the butter B located as 85 shown in the drawings, the said butter comprising a plurality of butting elements or devices having a construction similar to the main stemming mechanism hereinafter to be described in detail, it being here premised 90 that the butting mechanism consists generally in a pair of superposed stemming elements each provided with a plurality of thin flexible blades, the blades of one stemming 95 device intermeshing with the blades of the other stemming device, as generally indicated in Figure 1 of the drawings. In lieu of providing the butting mechanism in the position adjacent the conveyer belt 10, I may provide the butting mechanism such as B' 100 in a position to effect the butting operation after the leaves have been subjected to the main stemming activity. For the purpose of providing a resisting pressure opposed to the pull of the butting mechanism during 105 butting action, I may provide the plurality of rollers 23 (see Figures 1 and 3) journaled in the longitudinally arranged bar 24, the said rollers contacting the lower bight of the chain 16 and effecting a secure clamping 110 of the leaves between the said chain and the conveyer belt 10 during butting activity. After passing through the butter B the butt ends of tobacco leaves are carried over a plate 25, the said plate being provided at 115 its advance end with an upturned portion 26, terminating in a tongue 26' this functioning to flex the butt ends of the leaves and to turn them up to condition the same to be effectively gripped in the further operation 120 of the machine, as will become clearer presently.

For gripping the leaves and feeding the same in the further operation of the machine I provide the gripping mechanism G 125 hereinbefore referred to, the said gripping mechanism comprising preferably the sheave 27 fixed to a sleeve 28 rotatable in the upstanding post 29, the peripheral groove 30 of the said sheave receiving the strap or 130

cable 31, the said cable 31 being driven by rotation of the sheave 27. The sheave is provided with a plurality of peripheral pockets 32 arranged about the complete circumference of the sheave, the said pockets being intended for receiving the butt ends of the leaf stems. The sheave 27 is constructed to provide a circumferential upstanding flange 33 and in the circumferential recess 34 between the flange 33 and the body of the sheave 27 I provide the annular member 35 preferably made of rubber. As the tobacco leaves are further advanced by the feeding means the butt ends 15 of the leaves are turned up by the plate portion 26 as hereinbefore recited and are frictionally fed by contacting the cable 31, as clearly appear from Figure 1 of the drawings, the said butt ends of the leaves being 20 caught by the walls between the pockets 32, the said walls such as 36 acting in effect as directing fingers to direct the butting of the stems into the pockets 32 and cause the same to lodge therein and be firmly gripped between the cable 31 and the resilient annular 25 member 35, the pressure between these parts and the upturning of the butts resulting in the obtaining of a positive and secure hold for each stem.

30 Cooperating with the gripper sheave 27 I provide the opposed pulley or wheel 37 rotatably mounted in a swinging bracket 38, the latter rotatable in a stud 39. The pulley or wheel 37 is preferably movably 35 and resiliently mounted relatively to the sheave 27, this to the end of lending flexibility to the cable 31 and preventing undue strain when the stems crowd under the cable 31 and move into the gripper sheave 27. For 40 this purpose I provide the adjustable set screw 40, adjustable in bracket 41 forming part of the framework of the machine, and interposed between the shank of the set screw 40 and an arm 42 forming part of 45 the bracket 38 I arrange the compression spring 43, these parts being operative to swing the pulley 37 against the cable 31 to keep the latter in taut condition, as will be apparent.

50 After the stems are gripped by the cable and gripper sheave, the leaves emerge from under the binder chain or belt 16 and enter the stemming mechanism S. As hereinbefore referred to, one of the prime desiderata 55 of my present invention comprehends a stemming mechanism in which the web of the leaves may be cleanly cut close up to the stem without cutting the stem itself or unduly tearing the web and in which the removal of the web may be effected with a minimum of breaking strain exerted on the stem and in which the blades of the stemming mechanism may be kept constantly in good cutting condition irrespective of the grinding action of the sand on the leaves.

To these ends my stemming mechanism comprises stemming devices provided with a plurality of thin flexible blades, and more particularly a pair of rotatable stemming devices each carrying a plurality of thin 70 flexible blades, the blades of one device intermeshing with blades of the other device and adapted for receiving therebetween the stems of the leaves, with the latter fed to thread through the meshes of the blades, the 75 blades laterally flexing to accommodate varying thicknesses of the stems and acting on the web close up to the stem for cutting the same with a draw-clearing effect. Referring now to the drawings, the stemming 80 devices comprise the vertically aligned rotatable shafts 44 and 45 journaled in the framework 46, the said framework being provided at one end with the directing noses 47 and 48, the said shafts being each provided with a plurality of the spaced blades. Spined to each shaft I preferably provide a tube such as 49 and on the tube are spined in spaced relation a plurality of blades b, (see particularly Figure 4) spacing collars 85 50 being provided to properly space the blades along the axes of the said shafts 44 and 45. The shafts and the blades are rotated in opposite directions, as will become clearer hereinafter, and to this end the 90 shafts are provided with the intermeshing gear wheels 51 and 52.

The blades b are contoured circumferentially to provide a plurality of lobes l (see Figures 5 to 7) and a plurality of troughs t intermediate the lobes, this for a purpose as will become clearer presently. The blades b on one shaft are arranged in between the blades on the other shaft as is clear from the drawings, the blades being 100 thus arranged in intermeshing relation. The blades b are preferably made of thin flexible steel, these blades being uniformly thin. As an example of the thicknesses of the 105 blades it may be stated that these will vary for different kinds of tobacco and may be from .010 to .020 inch thick for the blades at the entrant end of the stemming devices where the more tenaciously adhering parts of the web are treated; and from .005 to .010 inch for the blades at the exit end of the stemming devices where the weaker parts of the leaves are treated. To accommodate the thicker parts of the stems at the 110 entrant end and to act more efficiently on the thinner stem portions at the exit end of the stemming devices, the blades are spaced with progressively diminishing distances between the blades from entrant to exit end, as will be clear for example from a consideration of Figure 4 of the drawings.

115 For stemming purposes the leaves are fed between the intermeshing blades, the leaves being fed as by drawing the stem in a direction oblique to the axes of the stemming de-

vices and in a resultant direction having components in the direction of the said axes and in a direction normal thereto. When so fed the stems are caught by the lobes of the blades and directed between the meshes of the successive blades, the stem of the leaves threading through successive blades, lapping first over one lobe of one blade and then over a lobe of a succeeding blade, as is shown clearly in Figures 2 and 5 to 7 and especially Figure 9 of the drawings, the blades acting during this stem feeding to progressively strip the leaf web from the leaf stem by cutting the same. This cutting may be described as a draw-cleaving, the draw-cleaving being obtained by rotating the blades as shown by the arrows in Figure 5 of the drawings, this to effect a cutting in opposition to the draw or pull exerted on the leaves as they are fed and threaded through the blade meshes by the gripping means G. With the provision of this construction a clean cut in the web is effected close up to the stem with little strain on the stem, the blades flexing to accommodate the varying thicknesses of the stems, the edges of the blades, even though gradually ground away by the gritty material carried by the leaves, never dulling the draw-cleaving edges beyond the thickness of the metal, the edges resulting from the grinding being the ideal draw-cleaving edge capable of separating the veins and web from the leaf but incapable of actually severing the stems.

In Figure 5 of the drawings I have shown the blades b each provided with four lobes but it will be apparent that any number of lobes may be provided, Figure 7, for example, showing the blades used in the butting devices provided with six lobes. This latter construction may be preferred because when the leaves are engaged in the troughs t with this construction each trough embraces fully one-half of the stem circumferentially, the blades of each stemming device therefore treating one-half the stem circumferentially, the leaves being treated by both stemming devices substantially the full circumference thereof, this assuring complete stemming of the leaves. The lobes l of the blades may all be arranged in longitudinal alignment or may be arranged in stepped relation as shown in Figure 5 so that the lobes may be traced in a helical form about the shafts 44 and 45.

For the purpose of feeding the leaves through the blades in the manner referred to and for the further purpose of providing for a greater draw-cleaving at the tougher stem portions adjacent the butt ends and a diminished draw-cleaving at the weaker stem portions adjacent the tip ends, I preferably arrange the stemming devices with their axes tangentially to the periphery of the gripper sheave 27, as clearly shown in Figure 5.

ures 1 and 2 of the drawings. With the provision of this arrangement the stems at the entrant end of the stemming device remain longer in the meshes of the revolving stemming devices, the tougher and more tenaciously adhering parts of the web being here subjected to greater draw-cleaving action than the weaker portions treated at the exit end of the stemming devices; and with this mechanism the leaves are fed in the desired direction oblique to the axes of the stemming devices to effect the interweaving and threading of the stems through the meshes of the blades, as is apparent from a consideration of, for example, Figure 2 of the drawings. In the operation of these parts any stems that have previously been broken or have lost their tenacity through fermentation or rot or those imperfectly gripped will be thrown back by the stemming elements into the chute or bin 53 provided for this purpose and all the stems which are secure enough to stand the continuous draw-cleaving action are carried along and away from the stemming elements while the web portions remain behind and are finally detached from the stems completely and dropped into the adjacent chute 54.

For the purpose of cutting the stem intermediate its ends adjacent the tip during the stemming of the leaves when such is desired, I provide the cutting means comprising the circular cutter 55 fixed on the shaft 44 and the cutter 56 on the shaft 45, the latter being contoured as shown in Figure 6 of the drawings to provide a plurality of lobes l'. When the stems carrying the loose web arrive at the cutters the stems will lap over one of the lobes of the cutter 56 and be carried against the edge of the circular cutter 55 and be severed. For the purpose of cutting the stem off as close to the attached web as possible I increase the space between the stemming blades and cutters (see Figure 4 for example) so that the stem and attached web will be drawn into the cutting elements without any further stripping or stemming action.

For the purpose of combing the web or lamina off the revolving blades of the stemming devices during stemming activity I preferably provide the combs or shields 57 and 58 arranged for cooperation respectively with the upper and lower sets of blades, these combs being attached to the framework 46, as clearly shown in Figures 3 and 4 of the drawings. I may also provide vapor or air pipes 59 and 60 with a plurality of spaced nozzles n directed into the meshing blades of the stemming devices. The pressure of vapor within the pipes creates a blast which is directed to meet in the meshes of the stemming element and results in a blast along the tobacco stem toward the web portion. This action assists the combs to

keep the web clear of the blades and the vapor also serves to prevent the web crumpling unduly. The vapor can be either low pressure saturated steam or water ladened air or dry air.

The stems after stripping the leaves, are carried around the gripper sheave 27 to where the cable 31 leaves the sheave and if butting of the leaves has not previously been effected, the stems are now subjected to butting action. The stems, as they are released from between the cable and sheave, are received by the traveling straps or cables 61 and 62, the said straps being trained over a plurality of sheaves such as 63 suitably journaled in the framework of the machine. The stems are carried along by the traveling straps with the adhering lamina on the butt ends thereof, as shown in Figure 1 of the drawings, and are subjected to the stemming action of the blades of the butter B', the said butter having stemming blades similar to the main stemming devices as shown, for example, in Figure 7 of the drawings, the tobacco flakes obtained during this butting falling into a chute 64 provided for this purpose. The stems, after the cutting operation, are dropped into the chute 65 (see Figure 1 of the drawings). Although I have shown two butting devices in Figure 1 of the drawings, in practice I prefer using a single butter arranged either before or after the main stemming devices. With some tobacco the after butting may be preferred and with other tobaccos the primary butting preferred, tobacco being stemmed either way with equal facility.

For the purpose of preventing the stems from sticking to the groove of the gripper sheave 27 or to the cable 31, I provide a moistening device comprising a rotatable cup 66 rotatable on the post 67, the said cup being provided with a wick 68 folded from the inside of the water cup over the walls and down the outside thereof, the said wick feeding water contained in the cup to a rubber tire 69 encircling the grooved wheel 70 rotating with the cup 66, the said rubber tire rotating in the groove of the gripper sheave 27, keeping the latter moist to prevent the stems from sticking. The moistening device, as is apparent, will be rotated by contact with the gripper sheave. Should the stems cling to the gripper sheave or the cable, they may be effectively removed by the scrapers s' and s² provided for this purpose.

The various parts of the apparatus may be driven from a main shaft 71, the latter adapted to receive motion from a prime mover (not shown) connected to a fly wheel 72 through the belt 73, a preferably hand operated clutch mechanism 74 being provided for connecting and disconnecting the main shaft 71 to and from the power. The

sheave 27 is positively driven from the main shaft 71 and to this end the shaft is provided with a worm 75 meshing with a worm wheel 76 fixed to the sleeve 28 of the sheave 27. For driving the stemming elements S one of the shafts such as 44 is provided with a sprocket wheel 77 connected by means of a sprocket chain 79 to an opposed sprocket wheel 78 fixed to the main shaft 71, this gearing being enclosed by the gear casing 80. The feeding mechanism F is also positively driven from the main shaft and to this end I preferably provide a cross shaft 81 journaled in bearings 82, the said cross shaft being provided with the worm wheel 83 meshing with the worm 84, the latter being attached to the main shaft 71; the said shaft 81 being in turn connected for driving the drum 12 of the feeding mechanism F by means of the sprocket wheels 85 and 86 and the interposed sprocket chain 87. For rotating the blades of the butter B I may provide the sprocket chain 88 trained over sprockets 89 and 90, the former being fixed to the main shaft 71 and the latter being fixed to a stub shaft 91, the gear wheel 92 on the said stub shaft meshing with the gearing 93 of the butter B. For rotating the blades of the butter B' in case the latter is used, I may provide the belt 94 traveling over the pulleys 95 and 96, the former being fixed to the main shaft 71 and the latter to one of the shafts of the butter B', the shafts of the butter being rotated in opposite directions by means of the gearing 97. If this butter B' is used the traveling straps or cables 61 and 62 may be operated by means of the pulley 98 attached to a shaft of one of the sheaves 63, the said pulley receiving motion from the main shaft through a belt 99.

The operation of my stemming machine will, in the main, be apparent from the above detailed description thereof. It will be apparent that as the leaves are untied from the "hands" they are spread by the operator on the conveyer belt 10, the leaves being fed between the belts 10 and 16 through the primary butter B if preliminary butting is desired, the leaves being then advanced with the cleared butt ends in between the gripper sheave 27 and the cable 31, the leaves being separated by the fingers of the gripper sheave and securely clamped and gripped for the stemming operation. The leaves are then advanced and fed into the blades of the stemming mechanism S, the gripper sheave drawing the leaves along and through the meshes of the blades of the stemming mechanism, the blades stripping the lamina from the stems with a draw-cleaving effect. The removed web or lamina drops into the chute 54 and the stems are carried by the gripper sheave for subsequent butting operation through the butter B' if

no preliminary butting has been previously effected, the stripped stems being then dropped into the chute 65.

While I have disclosed my stemming machine with great particularity, showing a specific embodiment thereof, it will be apparent that numerous changes may be made therein within wide variations without departing from the spirit of the invention, defined in the following claims.

I claim:

1. In a tobacco stemming machine, stemming mechanism including flexible blades arranged for rotation and for stemming the tobacco by a cutting action and means for drawing the tobacco leaves through the said blades in a direction opposing the cutting action thereof whereby the lamina of the leaves is stripped from the stem with a draw-cleaving effect.

2. In a tobacco stemming machine, stemming mechanism comprising a plurality of cooperating stemming devices, each device provided with flexible cutting blades, the blades of one device being arranged to intermesh with the blades of the other device and means for feeding the tobacco leaves through the said intermeshing blades for stemming the same.

3. In a tobacco stemming machine, stemming mechanism comprising a plurality of stemming devices, each device provided with a plurality of flexible blades arranged for stemming the tobacco by a cutting action, the blades of one device being arranged to intermesh with the blades of the other device and means for feeding the tobacco leaves through the said intermeshing blades for stemming the same; the said means being effective for drawing the leaves through the blades in a direction opposing the cutting action thereof whereby the lamina of the leaves is stripped from the stem with a draw-cleaving effect.

4. In a tobacco stemming machine, stemming mechanism including a plurality of thin laterally flexible blades each of a substantially uniform thinness arranged for rotation and for stemming the tobacco by a cutting action and means for drawing the tobacco leaves through the said blades in a direction opposing the cutting action thereof whereby the lamina of the leaves is stripped from the stem with a draw-cleaving effect.

5. In a tobacco stemming machine, stemming mechanism comprising a plurality of stemming devices, each device including a plurality of uniformly thin flexible blades arranged for stemming the tobacco by a cutting action, the blades of one device being arranged to intermesh with the blades of the other device and means for feeding the tobacco leaves through the said intermeshing blades for stemming the same.

6. In a tobacco stemming machine, stemming mechanism comprising a plurality of flat flexible blades arranged in parallel planes for rotation about an axis and means for drawing tobacco leaves through said blades to be stemmed thereby, the construction being such that the direction of draw or pull of the said drawing means is at an angle to the planes of the blades whereby the leaves are caused to travel through the meshes of the blades in the direction of said axis.

7. In a tobacco stemming machine, stemming mechanism comprising a plurality of cooperating stemming devices, each device provided with flexible blades, each blade being contoured to provide a plurality of lobes and intermediate trough portions, the blades of one device being arranged to intermesh with the blades of the other device and means for feeding the tobacco leaves through the said intermeshing blades for stemming the same.

8. In a tobacco stemming machine, stemming mechanism including rotatable flexible blades arranged for rotation on an axis and operative for stemming the tobacco by a cutting action, means for advancing the tobacco leaves to the said blades in the direction of said axis and means for drawing the leaves for stemming through the blades in a resultant direction having components in the direction of the said axis and in a direction normal thereto.

9. In a tobacco stemming machine, stemming mechanism comprising a plurality of cooperating stemming devices, each device provided with flexible blades, means for advancing the tobacco leaves to the said blades in the direction of the axes of said devices and means for drawing the leaves for stemming through the blades in a resultant direction having components in the direction of the said axes and in a direction normal thereto.

10. In a tobacco stemming machine, stemming mechanism comprising a plurality of cooperating stemming devices, each device provided with flexible blades, the blades of the devices being arranged in intermeshing relation, means for advancing the tobacco leaves to the said blades, the said means comprising an endless belt having a flight lying in a plane between the axes of the said devices and means for receiving the leaves from the said advancing means, the said last mentioned means being constructed for gripping the leaves and drawing them through the intermeshing blades in a direction having components in a direction along the said axes and in a direction normal thereto.

11. In a tobacco stemming machine, stemming mechanism comprising a stemming device provided with a plurality of thin laterally flexible blades disposed along the axis of

the device and adapted for receiving there-between the stems of the leaves and for stemming the same by a cutting action.

12. In a tobacco stemming machine, stemming mechanism comprising cooperating stemming devices each provided with thin flexible blades arranged along the axes of the devices and adapted for stemming tobacco leaves by cutting action.

13. In a tobacco stemming machine, stemming mechanism comprising a set of stemming devices each provided with a plurality of thin flexible blades, the blades of one device intermeshing with the blades of the other device and adapted for receiving there-between the stems of the leaves and for laterally flexing to accommodate the varying thicknesses of the stems.

14. In a tobacco stemming machine, stemming mechanism comprising devices each provided with a plurality of thin flexible blades, the blades of one device intermeshing with the blades of the other device, each of the said blades being contoured to provide a plurality of lobes and troughs intermediate the lobes.

15. In a tobacco stemming machine, stemming mechanism comprising a plurality of stemming devices each provided with a plurality of thin flat flexible blades arranged along the axis of the devices and cutting mechanism arranged on the devices at the advance end thereof.

16. In a tobacco stemming machine, a rotatable gripping means and a rotatable stemming means having its axis of rotation substantially tangentially to the periphery of the gripping means, the said stemming means comprising flexible blades adapted for stripping the leaves by a cleaving action.

17. In a tobacco stemming machine, a rotatable gripping means and a rotatable stemming means having its axis of rotation substantially tangentially to the periphery of the gripping means, the said stemming means comprising a plurality of uniformly thin laterally flexible blades spacedly arranged in the direction of said axis of rotation.

18. In a tobacco stemming machine, a rotatable gripping means comprising a gripper sheave and rotatable stemming means comprising a plurality of stemming devices each arranged substantially tangentially to the periphery of the gripper sheave, each device carrying a plurality of parallelly arranged flexible blades each of uniform thinness.

19. In a tobacco stemming machine, stemming mechanism comprising a plurality of stemming devices provided with flexible blades, a gripper mechanism comprising a gripper sheave and a belt cooperating therewith, means for advancing tobacco leaves in the direction of the said stemming devices,

the said advancing means being arranged to feed the leaves to the said gripper mechanism with the said leaves gripped between the sheave and the belt, said gripper mechanism being effective for feeding the leaves to and through the stemming blades.

20. In a tobacco stemming machine, a gripper mechanism comprising a gripper sheave and a belt movable thereabout and driven thereby, the cooperating being such that the stems of the tobacco leaves are gripped between the belt and the sheave and so fed for stemming activity.

21. In a tobacco stemming machine, a gripper mechanism comprising a gripper sheave with a peripheral groove, the periphery of the groove being contoured to provide a plurality of peripheral pockets, a belt movable about the sheave and frictionally driven thereby, the construction being such that the tobacco leaves are gripped between the belt and sheave with a leaf stem received and held in a peripheral pocket.

22. In a tobacco stemming machine, a gripper mechanism comprising a rotatable gripper sheave having a peripheral groove, an opposed wheel in the plane of said sheave, a belt trained over the wheel and sheave, the construction being such that the leaves fed to the sheave will be gripped in the groove therein between the sheave and the belt and so fed for stemming activity.

23. In a tobacco stemming machine, a gripper mechanism comprising a rotatable gripper sheave having a peripheral groove, a wheel, a belt trained about the wheel and sheave, the construction being such that the leaves fed to the sheave will be gripped in the groove therein between the sheave and the belt and so fed for stemming activity; the said wheel being movably and resiliently mounted with respect to the said sheave.

24. In a tobacco stemming machine, a gripper mechanism comprising a gripper sheave and a belt movable thereabout and cooperating therewith and means for feeding leaves between the gripper sheave and belt, the said means including elements operative on the butt ends of the stems for turning the same up and feeding the same between the sheave and the belt.

25. In a tobacco stemming machine, a gripper mechanism comprising a gripper sheave and a belt movable thereabout and cooperating therewith and means for feeding leaves between the gripper sheave and belt, the said means including elements operative on the butt ends of the stems for turning the same up and feeding the same between the sheave and the belt, the said elements comprising a plate terminating in an upturned tongue portion adjacent the groove of the sheave.

26. In a device of the class described, means to move tobacco leaves laterally and

longitudinally in succession, and a succession of flexible cutting blades engaging the leaves at opposite sides of the stem and cutting in the opposite direction to their longitudinal movement.

27. In a device of the class described, a plurality of cooperating series of cutting blades moving in one direction, and means

to draw tobacco leaves in the opposite direction and to move the leaves laterally thereby 10 to be engaged by the blades in succession.

Signed at Lynchburg, in the county of Campbell and State of Virginia this 19 day of January, A. D. 1922.

FREDERICK C. SCHOFIELD.
